UNITED STATES PATENT OFFICE.

ANTON J. HAUG, OF NASHUA, NEW HAMPSHIRE.

MECHANICAL STARTER FOR EXPLOSIVE-ENGINES.

1,305,720.

Specification of Letters Patent.

Patented June 3, 1919.

Application filed July 12, 1917. Serial No. 180,208.

To all whom it may concern:

Be it known that I, ANTON J. HAUG, a citizen of the United States, residing at Nashua, in the county of Hillsborough and 5 State of New Hampshire, have invented certain new and useful Improvements in Mechanical Starters for Explosive Engines, of which the following is a specification.

This invention relates to mechanical devices for starting gas or explosive engines.

My purpose is to provide a device which is so actuated by a single power spring as to impart a few revolutions to the main shaft of such an engine whereby charges are 15 drawn in, mixed, compressed and ignited until the engine starts running.

A further object of my invention is to provide simple and compact means by which as the engine continues to run, it can be so 20 connected that it will wind up the power spring and that when the spring is wound up, the connection is automatically broken.

In the drawings, Figure 1 is a front elevation of the device with the casing shown 25 in section and the spring being wound up. Fig. 2 is an elevation as from the left of Fig. 1 with the casing removed. Fig. 3 is a plan view with the casing removed. Fig. 4 is a vertical sectional elevation on line 4—4 of 30 Fig. 3 of the gears, drums, etc., surrounding the starting shaft, the starting shaft itself not being in section. Fig. 5 is an enlarged section from the right on line 5—5 of Fig. 4. Fig. 6 is an enlarged section on line 35 6—6 of Fig. 4. Fig. 7 is a side elevation of the brake, brake-bar, and foot pedal. Fig. 8 is an enlarged detail section of the automatic cut-off mechanism from the right of line 8—8 of Fig. 2, but showing the spring 40 unwound.

Adjacent to the engine and preferably at one side thereof, is the frame A which is fixed to the chassis preferably along side of the engine in any suitable manner, not 45 shown. To the upright portion 10 of this frame is fixed a gear shaft 11. Revolvable upon shaft 11 is a starting gear B fixed to a sleeve 21 through which shaft 11 passes. This gear is hollowed out at 22 to receive 50 the power spring C, the outer end of which is fixed to starting gear B by means of a pin 23.

Adjacent to starting gear B is winding gear F which is fixed to a sleeve 30 revolvable 55 on sleeve 21 and having a screw threaded portion 31.

Winding gear F is hollowed out at 32 on the face which adjoins spring C and starting gear B, and the inner end of power spring C is fixed to sleeve 30 at 33.

Winding gear F also is formed with a ratchet 34 with which engages a pawl 35 pivoted to frame A whereby gear F can revolve only in a direction which will carry along that end of spring F which is attached to sleeve 30 at 33 in such manner as to wind up the spring if the other end is held fast.

This arrangement will cause spring C when wound up to unwind carrying with it 70 starting gear B in the same direction that gear F travels when winding up the spring.

G is a reducing starting gear in engagement with gear B fixed to and carried by a starting shaft 40 carried in bearings in 75 frame A.

At its other end, shaft 40 carries a ratchet 41 which engages pawls 42 carried by means which connect it with the main motor shaft H. This motor shaft H is shown as carrying a diagonal gear 50 which meshes with a gear 51 with which is also integral a clutch drum 52 which carries the pawls 42. Gear 51 and drum 52 are revolvable on starting shaft 40.

These parts are all so arranged that when spring C unwinds, it revolves main starting gear B, reducing starting gear G, starting shaft 40, ratchet 41, pawls 42, drum 52, gears 51 and 50, and main engine shaft H 90 in a direction to start the engine.

To hold the power spring C under tension, I prefer to use a brake drum 44 which is shown as integral with gear G and which must be revolvable with shaft 40 to which it 95 is made fast by set screw 38.

This brake drum 44, brake strap 45 of any usual construction, pivoted arm 46 to one end of which strap 45 is attached, and brake rod 47 attached at one end to the other end 100 of arm 46 and at its other end to a foot lever 48 of any usual construction constitute the starting means holding devices by which the power spring is prevented from unwinding. When the brake is set, ratchet 91 and pawl 105 90 of any usual type hold it set.

When the spring is wound up and it is desired to start the engine, the brake is released by releasing pawl 90 and the engine is started.

K is a reducing winding gear which engages main winding gear F and is carried by

60

110

a sleeve 60 slidable and rotatable on starting shaft 40. Sleeve 60 also carries a clutch member 61 which has a flange 81 and is adapted to engage clutch drum 52 when slid 5 into engagement therewith.

Gear K is shown as slidable on sleeve 60, but revoluble therewith by reason of a slot 62 into which enters a key projection 63 on sleeve 60 as shown in Fig. 6.

10 When the engine has started, the brake should be applied thus holding shaft 40 against rotation, but permitting the gear 51 and clutch drum 52 to revolve freely.

It will be seen that if clutch member 61 is 15 slid into engagement with drum 52 after the engine has started, it together with gears K and F will revolve winding up power spring C for the next starting operation.

This engaging might be done by the hand, 20 but I prefer to use a collar 70 which embraces sleeve 60 and is carried at the end of a member 71 carried by arms 72 fixed to another member 73 which is shown as a pivoted rod which also carries an arm 74 operable through the medium of another rod 75, 25 suitably connected thereto, which is slidable in bearings 76, 76 and has a head 77 within convenient reach of the driver.

I find it desirable however to provide 30 automatic shut-off mechanism to prevent the spring from being wound up too tight. The mechanism which I prefer includes fingers 80 which are proximate the side of a flange 81 on clutch member 61 which is opposite 35 from collar 70. These fingers are joined together in an arm 86 the end of which fits in an annular groove on a threaded collar 82 which is screwed onto the threaded section 31 of sleeve 30. This collar 82 carries pins 40 83, 83 which pass through holes 84 in a plate 85 fixed to starting gear sleeve 21.

When the starting gear B turns, collar 82 is screwed outward to the position shown by the full lines in Fig. 8, carrying arm 86 and 45 fingers 80, 80 away from flange 81, but when the starting mechanism is stopped and the winding mechanism is thrown into operation, gear F and its sleeve 30 revolve causing collar 82 to be screwed back to the position 50 shown in the dotted lines carrying with it arm 86 and fingers 80, 80 until they engage flange 81 and force it with clutch member 61 out of engagement with clutch drum 52 thus stopping the winding up operation.

55 The ratchet 34 and pawl 35 are the means shown to prevent the main winding gear and main starting gear from moving except in one direction. The ratchet 41 and pawls 42 are the means which connect the starting gear shaft with the engine shaft and which cause the latter to revolve or permit it to revolve in only one direction. The sleeve 60 may be considered as a part of clutch member 61. It is manifest that various other

means besides those shown could be used in place thereof.

My device is simple, compact, and has few parts. If the brake, or other means for holding the starting mechanism from revolving, is not set, no harm is done, and if the winding means is not engaged by the action of collar 70, no harm is done except that in either case, the device does not work. After the winding means has started, the automatic shut-off device stops it at the right 75 predetermined point.

I prefer to make the starting gear smaller than the winding gear or the reducing winding gear smaller than the reducing starting gear, or both as shown, so that the winding 80 means will work more slowly but with more power than the starting means.

All the revoluble parts of my device are so arranged that they can turn in only one direction, and there is no chance that, by an 85 improper manual setting of the parts, anything should be broken.

If the brake or other means for holding the starting mechanism is released and the clutch members 61 and 52 are, by mistake, 90 engaged with the purpose of winding up the spring, no harm is done; for in such a case the spring carrying with it the starting gear and other parts simply follows the winding gear, the sleeves 30 and 21 turning together, 95 and the automatic stopping mechanism does not act.

I claim:

1. In a mechanical starting device for automobile engines, the combination of a 100 main starting gear, a main winding gear, and a spring one end of which is attached to the main starting gear and the other to the main winding gear, with means to prevent the main winding gear from moving 105 except in one direction, a starting shaft, a reducing starting gear carried thereby in engagement with the main starting gear, a clutch drum revoluble with the main engine shaft, means which connect it with the starting gear shaft which cause it to revolve therewith in one direction, a reducing winding gear in engagement with the main winding gear, and a clutch member 110 slidable on the starting gear shaft revoluble with the reducing winding gear and adapted to engage the clutch drum as described.

2. In a mechanical starting device for automobile engines, the combination of a 120 main starting gear, a main winding gear, and a spring one end of which is attached to the main starting gear and the other to the main winding gear, with means to prevent the main winding gear from moving 125 except in one direction, a starting shaft, a reducing starting gear carried thereby in engagement with the main starting gear, a

clutch drum revoluble with the main engine shaft, means which connect it with the starting gear shaft which cause it to revolve therewith in one direction, a reducing winding gear in engagement with the main winding gear, a clutch member 5
slidable on the starting gear shaft, revoluble with the reducing winding gear and adapted to engage the clutch drum, a manually 10
operable brake adapted to hold the starting mechanism, and manually operable mechanism for engaging the clutch member with the clutch drum.

3. In a mechanical starting device for 15
automobile engines, the combination of a main starting gear, a main winding gear, and a spring one end of which is attached to the main starting gear and the other to the main winding gear, with means to prevent 20
the main winding gear from moving except in one direction, a starting shaft, a reducing starting gear carried thereby in engagement with the main starting gear, a clutch drum revoluble with the main engine 25
shaft, means which connect it with the starting gear shaft which cause it to revolve therewith in one direction, a reducing winding gear in engagement with the main winding gear, a clutch member 30
slidable on the starting gear shaft, revoluble with the reducing winding gear and adapted to engage the clutch drum, a manually operable brake adapted to hold the starting mechanism, manually operable mechanism for engaging 35
the clutch member with the clutch drum, and an arm carried by the threaded collar on the winding gear sleeve adapted to automatically disengage the clutch member from the clutch drum.

4. In a mechanical starting device for 40
automobile engines, the combination of a fixed gear shaft, a starting gear sleeve revoluble thereon, a starting gear carried by such sleeve, a threaded winding gear sleeve, 45
a winding gear carried by such sleeve, a threaded collar carried by the winding gear sleeve having projecting pins, and a plate carried by the starting gear sleeve having pin holes through which the pins 50
project, with a spring one end of which

is attached to the main starting gear and the other end to the main winding gear, means to prevent the main winding gear from moving except in one direction, a starting shaft, a reducing starting gear 55
carried thereby in engagement with the main starting gear, a clutch drum revoluble with the main engine and shaft, means which connect it with the starting gear shaft which cause it to revolve and permit 60
it to revolve in one direction, a reducing winding gear of smaller size than the reducing starting gear in engagement with the main winding gear, a clutch member 65
slidable on the starting gear shaft and revoluble with the reducing winding gear which is adapted to engage the clutch drum, manually operable means adapted to hold the starting mechanism, manually operable means for engaging the clutch member 70
with the clutch drum, and an arm carried by the threaded collar on the winding gear sleeve adapted to automatically disengage the clutch member from the clutch drum.

5. In a mechanical starting device for 75
automobiles, the combination of a gear shaft, a main starting gear and sleeve revoluble thereon, a main winding gear and threaded sleeve revoluble on the starting gear sleeve, and a spring one end of which 80
is attached to the main starting gear and the other end to the main winding gear, with means to prevent the main winding gear from moving except in one direction, connections between the main starting gear 85
and the engine shaft adapted for starting the engine, connections between the main engine shaft including a clutch and the main winding gear adapted to wind up the spring, a plate having pin holes carried by the starting gear sleeve, a collar carried by the threaded portion of the winding gear sleeve having pins which pass through the pin holes in the plate, and an arm carried by the collar in operative engagement with 90
said clutch whereby it will disengage the clutch at a predetermined point.

In testimony whereof I have affixed my signature.

ANTON J. HAUG.
